RADIAL TRANSDUCER STRUCTURE

Carl H. Steenstrup, Schenectady, and Charles J. Falk, Scotia, N. Y., assignors, by mesne assignments, to the United States of America as represented by the Secretary of the Navy

Application March 26, 1951, Serial No. 217,443

1 Claim. (Cl. 340—11)

1

The present invention relates to improvements in transducers and more specifically to a radial underwater electroacoustic transducer.

An important object of the invention is to provide a transducer assembly adapted to transmit or receive acoustic energy radially but not longitudinally.

Another object of the invention is the provision of a transducer assembly adapted to withstand high external pressure.

A further object is to provide a transducer having its parts constructed and arranged for easy assembly.

A still further object is the provision of an improved watertight transducer assembly.

Other objects and advantages of the invention will become apparent during the course of the following detailed description, taken in connection with the accompanying drawing forming a part of this specification and in which drawing:

Fig. 1 is an end elevational view of the radial transducer.

Fig. 2 is a central longitudinal sectional view of the transducer assembly taken substantially on the line 2—2 of Fig. 1.

In the drawing, which for the purpose of illustration shows only a preferred embodiment of the invention and wherein similar reference characters denote corresponding parts throughout the views, the numeral 10 generally designates the transducer assembly comprising a hollow cylindrical acoustic rubber window 11 having its circumferential marginal edge portions 12, 13 mounted in suitably rabbeted rigid annular supports 14, 15.

These annular supports 14, 15 are so rabbeted as to provide inside telescopic walls 16, 17 and beveled end-abutting walls 18, 19 that are bonded to the annular window margins as by cycle-welding or cementing.

Affixed to one window support 14 as by cap screws 20 is a circular end cap 21 forming a watertight seal at one end of the transducer assembly.

Coaxially disposed within the hollow cylindrical window 11 is a rigid hollow cylindrical cup-like core 22 having its closed end wall 23 affixed to the end cap 21 by internal cap screws 24 so as to reduce the possibility of leakage into the transducer assembly. The external diameter of this core is less than the internal diameter of the hollow cylindrical window so as to provide an annular transducer space divided by a rigid electrically insulative annular radial load bearing wall 25 adapted to support the window at its

2

transverse central portion against external pressure. Occupying the annular transducer space on opposite sides of the bearing wall 25 are two annular transducer elements 26, 27, preferably of the magnetostrictive type. These transducer elements 26, 27 include leads 28—31 extending through slots 32, 33 in the core 22 and connected to an electrically insulative terminal board 34 within the core.

10 Affixed to the window support 15 as by cap screws 35 is a circular end cap 36 including an axial packing gland 37 adapted to provide a watertight seal for a suitable lead-in cable (not shown). The opposite end portions of the core 22 are fitted in circular coaxial recesses 38, 39 in the interior sides of the end caps 21, 36 thus providing a strong joint. The rigid metal parts of the transducer assembly including the core 22 are preferably formed of a non-magnetic material 15 such as aluminum. Accordingly the metal core 22 forms an electrical shield for the transducer leads and acts to prevent longitudinal as well as radial compression of the transducer assembly due to high pressure.

15 Compressed in suitable grooves in the end caps 21, 36 are packings such as O-rings 40, 41 insuring watertightness of the joints between the end caps and the window supports 14, 15. The gland 37 is also grooved to receive a packing such as an O-ring 42 to prevent ingress of water around the gland.

20 In operation, acoustic energy is radially transmitted to and received from the transducer elements 26, 27 by the cylindrical acoustic window 25 while the transmission and reception of acoustic energy axially of the assembly is blocked by the rigid end caps 21, 36. The annular partition wall 25 between the double row of transducers reinforces the window so that it can withstand high pressure on its outside surface. If more than two rows of transducer elements are provided, a reinforcing partition wall may be interposed between each adjacent pair of transducer rows.

25 In assembling the transducer, it is convenient to reach inside through the end cap openings in the window supports 14, 15 in order to cycle-weld or cement the transducer elements 26, 27 to the acoustic window 11.

30 Various changes may be made in the form of invention herein shown and described without departing from the spirit of the invention or the scope of the following claim.

35 What is claimed is:

A radial transducer comprising a hollow cylin-

drical shell of a material chosen for its ability to transmit acoustic energy, first and second rigid annular supports having flange portions and sleeve portions in respective end-abutting and inside-telescopic engagement with opposite end portions of said acoustic shell, said shell being bonded to said annular supports at said flange- and sleeve-engaging portions, a first rigid end cap having a marginal flange portion releasably affixed to said first annular support and a cylindrical plug portion telescopically fitting within said first support, said plug portion having an inside surface provided with a central recess, a rigid hollow cylindrical cup-like core axially disposed within the shell and having a closed end wall fitting within said recess and releasably fastened to said first end cap, a second rigid end cap having a marginal flange portion releasably affixed to said second annular support and a cylindrical plug portion telescopically fitting with said second support and provided with an opening

communicating with the interior of said core, said last-mentioned plug portion having an inside surface provided with an annular recess receiving said cylindrical core at its end opposite said closed end wall, means releasably affixing said last-mentioned plug portion to said core, said core being smaller in diameter than the inside diameter of said shell whereby an annular space is defined between said core, shell and end caps, an annular transducer element occupying said space, a packing gland releasably affixed to said second end cap in watertight sealing relation to said opening, and leads extending through said packing gland and hollow core to said transducer element.
